US00D799022S

(12) United States Design Patent (10) Patent No.: US D799,022 S
(45) Date of Patent: * Oct. 3, 2017

(54) MOUNTING CLIP FOR PORTABLE FAN

(71) Applicant: O2COOL, LLC, Chicago, IL (US)

(72) Inventor: Michael Ksiazek, Burr Ridge, IL (US)

(73) Assignee: O2COOL, LLC, Chicago, IL (US)

() Term: 15 Years

(21) Appl. No.: 29/581,189

(22) Filed: Oct. 17, 2016

Related U.S. Application Data

(63) Continuation of application No. 29/514,956, filed on Jan. 19, 2015, now Pat. No. Des. 770,033.

CLAIM

The ornamental design for a mounting clip for portable fan, as shown and described.

DESCRIPTION

FIG. 1 is a first perspective view of the mounting clip for portable fan;

FIG. 2 is a second perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines immediately adjacent the shaded areas represent the bounds of the claimed design while all other broken lines are directed to environment; the broken lines form no part of the claimed design.

1 Claim, 8 Drawing Sheets
